UNITED STATES PATENT OFFICE.

SAMUEL W. DOW, OF MALLARD, IOWA.

SAND-SCREEN.

SPECIFICATION forming part of Letters Patent No. 697,076, dated April 8, 1902.

Application filed November 29, 1901. Serial No. 84,086. (No model.)

To all whom it may concern:

Be it known that I, SAMUEL W. Dow, a citizen of the United States, residing at Mallard, in the county of Palo Alto and State of Iowa, have invented certain new and useful Improvements in Sand-Screens; and I do hereby declare the following to be a full, clear, and exact description of the invention, such as will enable others skilled in the art to which it appertains to make and use the same.

This invention relates to screens designed chiefly for sifting sand, and aims to provide a device of this character which can be readily transported and easily operated without producing the fatigue incident to the ordinary screen, against which the sand is thrown in the screening operation. The machine is constructed to admit of coarse and fine screens being interchangeably used, the screen having a jiggling or vibratory motion imparted thereto and the mechanism being operated either by hand or any convenient motive power.

For a full description of the invention and the merits thereof, and also to acquire a knowledge of the details of construction of the means for effecting the result, reference is to be had to the following description and drawings hereto attached.

While the essential and characteristic features of the invention are susceptible of modification, still the preferred embodiment of the invention is illustrated in the accompanying drawings, in which—

Figure 1 is a perspective view of a machine constructed in accordance with and embodying the essential features of the invention. Fig. 2 is a side view thereof. Fig. 3 is a perspective view of the lower or delivery end. Fig. 4 is an end view of the machine. Fig. 5 is a vertical longitudinal section of the upper or receiving end portion, showing the relation of the working parts. Fig. 6 is a section on the line X-X of Fig. 2 looking to the rear. Fig. 7 is a view of the machine inverted, the ground-wheels being omitted. Fig. 8 is a perspective view of the screen-holder, the vibratory supports therefor, and the screen, the latter being in position.

Corresponding and like parts are referred to in the following description and indicated

in all the views of the drawings by the same reference characters.

The frame comprises longitudinal bars 1, transverse bars 2, firmly connecting the bars 1, and legs or supports 3 and 4. When the machine is in position for use, the frame inclines to the horizontal and its lower end is supported by the legs 4, resting on the ground, and its upper end is supported by ground-wheels 5, fitted to the ends of the axle 6, fitted to the lower end of the supports 3. A hopper 7 is provided at the upper or receiving end of the machine, and the sand or other material to be screened is dumped therein and passes to the screen 8, located therebelow.

A screen-holder 9 is located below the frame and is supported in such a manner as to receive a lateral vibratory or shaking movement, and this holder may be of any construction to receive screens 8 of different-sized mesh, according as the material is to be screened coarse or fine. As shown, the longitudinal or side bars of the holder are grooved and the screen 8 is slid into the grooves, thereby admitting of either a coarse or a fine screen being placed in position, the screen being held in the holder by any suitable fastening means. Cross-bars 10 and 11 are secured to the screen-holder and the vibratory or swinging supports are pivotally connected at one end thereto. The lower supports 12 are pivoted at their upper ends to the legs 4, and their lower ends have pivotal connection with the projecting ends of the cross-bar 11. The upper supports 13 are pivoted at their lower ends to the legs 3 and at their upper ends to the ends of the cross-bar 10. The parts 12 may be properly termed "hangers," whereas the parts 13 are standards, and these supports bear against the side of the respective legs facing the receiving or upper end of the machine, with the result that the holder 9 and screen 8 cannot slip downward and are firmly supported against the weight of the material imposed thereon.

A shaft 14 is arranged transversely of the machine and is journaled in bearings applied to extensions 15, forming a part of the machine-frame, and this shaft is adapted to receive the power by means of which the screen is operated. Fly-wheels 16 are applied to the

ends of the shaft 14, and for manual operation a crank 17 is applied to an end of the shaft. A bevel-gear 18 is secured to the shaft 14 for rotation therewith and is in meshing 5 relation with a companion bevel-gear 19, mounted upon a stub-shaft 20, arranged about at a right angle to the shaft 14. A bell-crank lever 21 has one arm connected by a pitman 22 with a wrist-pin applied to the bevel-gear 19, so as to receive an oscillatory movement therefrom when the shaft 14 is rotated. A link 23 connects the opposite arm of the bell-crank lever with the screen-holder, so as to impart a lateral reciprocating movement thereto. A companion bell-crank lever 24 is mounted upon an arm projected from a transverse bar 25, connecting the legs 4, and one arm thereof is connected by a pitman 26 with the cross-bar 11 or other convenient portion of 20 the screen-holder, and the other arm of the bell-crank lever is connected by a rod 27 with the arm of the bell-crank lever 21, to which the pitman 22 is attached. When the shaft 14 is rotated, the bell-crank levers 21 and 24 25 are caused to oscillate in unison, and by reason of their connection with the screen or support therefor a lateral reciprocating or jiggling motion is imparted to the screen, and as the screen is transversely oscillated it at the 30 same time receives an up-and-down movement resulting from the oscillation of the supports 12 and 13, and this vibratory motion, in conjunction with the inclination of the screen, causes the sand or material to 35 pass thereover from the upper or receiving end of the screen to the lower or discharge end thereof, the material screened passing through the meshes and the screenings passing over the lower end of the screen.

By having the machine mounted upon 40 wheels 5 it can be easily transported from place to place, the projecting ends of the longitudinal bars 1 at the lower end of the machine serving as handles when trundling the machine. The hopper and driving mechanism being located at the receiving end of the machine, the weight thereof is supported directly upon the ground-wheels. Hence the machine can be readily moved by one person. By having the legs 4 resting upon the 50 ground the machine is not liable to displacement when in operation. The supports 3 and 4 are of different lengths, depending upon the desired inclination of the screen and the relative distance of the axle 6 from the ground. 55

Having thus described the invention, what is claimed as new is—

In combination, a frame, legs at opposite ends of the frame, a screen mounted on the frame for transverse reciprocation, hangers 60 supporting the delivery end of the screen and adapted to bear against the upper side of the lower legs, standards pivotally supporting the upper end of the screen, a transverse power-driven shaft mounted upon extensions of the 65 frame, upper and lower bell-crank levers connected for simultaneous oscillation, links connecting corresponding arms of the bell-crank levers with the screen, and gearing between the upper bell-crank lever and the power- 70 driven shaft, substantially as set forth.

In testimony whereof I affix my signature in presence of two witnesses.

SAMUEL W. DOW. [L. S.]
